UNITED STATES PATENT OFFICE.

ELLEN M. MYTTON, OF LOS ANGELES, CALIFORNIA.

DOLL.

Application filed November 2, 1925. Serial No. 66,211.

My invention relates to dolls and has for its principal objects, to generally improve upon and simplify the construction of the existing forms of so called "rag" dolls, i. e. 5 dolls that are flexible and unbreakable, by reason of the fact that they are constructed almost entirely of fabric and soft fibrous material; to provide a doll of the character referred to that has the head, arms and limbs 10 connected to the body in such manner that they may be readily moved into different positions; to provide relatively simple means for attaching the head, arms and limbs of the doll to the body; to provide relatively 15 simple means for creating in a rag or fabric doll, a modeled face and, further, to provide a novel arrangement whereby a doll's head may be formed with two faces, either one of which may be covered and hidden 20 from view by the depending portion of the hair that is applied to the doll's head.

With the foregoing and other objects in view my invention consists in certain novel features of construction and arrangement 25 of parts that will be hereinafter more fully described and claimed and illustrated in the accompanying drawings in which:

Fig. 1 is a front elevational view of a doll constructed in accordance with my in- 30 vention.

Fig. 2 is a vertical section taken length- 35 wise through the medial portion of the doll's head and body.

Fig. 3 is a detail section taken on the line 3-3 of Fig. 2.

Fig. 4 is a vertical section taken through 40 the lower portion of a doll's body and showing the limbs pivotally connected to the body.

Fig. 5 is an elevational view of the section 45 of fabric that is used for making a modeled face.

Fig. 6 is a vertical section taken on the line 6-6 of Fig. 5.

Fig. 7 is a vertical section taken through 50 the head member that is adapted to receive the modeled face.

Figs. 8 and 9 are elevational views partly 55 in section of a double faced doll constructed in accordance with my invention.

In the construction of the body B, head H, arms A and limbs L of my improved doll, the outer coverings or "skin" representing members are formed of soft, pliable 60 fabric 10, such as a stockinette or balbriggan and these members are stuffed or filled with

suitable fibrous material 11 such as cotton, curled hair or the like.

Arranged in the upper or shoulder portions of body B is a transversely disposed 60 reinforcing member 12, preferably of wire, the ends of which are bent into depending loops 13 and the central portion of this wire is bent to form a horizontally disposed loop 14 that coincides with a neck opening 15, the latter being formed at the upper central portion of the body covering.

Member 12 is designed to reinforce and hold the upper portion of the body in proper 70 shape.

Head representing member H is formed with a depending cylindrical member 16 that projects through opening 15 and loop 14 and extends downwardly into the upper portion of body B. This depending member 16 is free to rotate for a limited distance in both directions, and thus head member H and the face or features thereon may be turned from side to side.

Formed through the lower end of member 80 16 is an aperture 17, through which passes a cord or tape 18, and the latter extends downwardly through the central portion of body B.

Secured on the inner face of the lower portion of the body covering is a reinforcing member 19, preferably a tape, and formed in the center of the body covering adjacent to the edges of said tape are apertures or eyelets 20, through which pass cord 90 or tape 18.

Thus, the head H and its depending member 16 are firmly secured to body B and said head is mounted so that it may be turned from side to side.

Formed in the sides of body B at the upper end thereof are depressions or sockets 21, into which are fitted or rounded upper ends of the arm members A

To secure the arm members to the body, a cord or tape 22 passes through the upper portion of body B, in front of and behind member 16, said cord or tape being carried through the body and arm coverings and passing through discs or buttons 23 that are arranged in the upper ends of arm members A. Thus, the arm members are firmly secured to the body, and at the same time, said arm members are free to be moved 100 into different positions.

The lower ends of arm members A are

stitched and modeled so as to represent the hands and fingers. Likewise the lower ends of the leg members L are modeled and stitched to represent the feet and toes.

5 In some instances, the upper end of limb members L may be sewn directly to the lower portion of body B, as illustrated in Fig. 1, or as illustrated in Fig. 4, the rounded upper ends of the leg members may be mounted 10 in sockets 24 that are formed in the lower end of the body.

When the latter arrangement is carried out, the leg members are connected to the body by a cord or tape 25 that passes 15 through the lower end of the body and through buttons or discs 26 that are positioned within the upper ends of said leg members. (See Fig. 4.)

Head member H may be painted or stenciled to represent a face, and likewise may be painted or stenciled to represent hair, or if desired, natural hair may be secured in any suitable manner on the top and back of the head member.

25 In the event that it is desired to provide the doll with a modeled face, the head member H is made in the form of a semi-spherical member with a substantially flat front surface, as illustrated in Fig. 7.

30 To provide the modeled face, a substantially oval section of material 26 such as cardboard is spaced a slight distance to the rear of a larger substantially oval section 27 of fabric. With a thread and needle, the 35 outline of the eyes, nose and mouth are stitched through the fabric and cardboard member, and at the same time, soft, fibrous material such as cotton is packed between the sections of cardboard and fabric and 40 worked so as to produce the outline and contour of the facial features. This formation of a modeled face is greatly facilitated by drawing the thread taut or leaving the same loose in making the stitches around the 45 facial features, and at the same time, packing the fibrous material to give the desired contour. When the modeled face has thus been produced, the edges of fabric section 27 are turned inwardly so as to overlie the 50 edges of the cardboard and the fibrous material applied thereto, and the entire member is now fitted onto the front flat surface of the semi-spherical head and secured thereto preferably by means of stitches taken with 55 a needle and thread.

The modeled face thus produced may be painted or colored as desired. My invention also contemplates the formation of two faces on one head member and the two faces may be entirely different in appearance or they may represent the same face under different conditions, for instance, one face with the eyes open and the other face with the eyes closed as in sleep. When this 60 arrangement is carried out, the two different 65

faces are formed or painted on opposite sides of the head member as illustrated in Figs. 8 and 9 and secured on top of the head is a body 28 of natural or artificial hair that is of sufficient length to cover both of 70 the faces.

Secured to the lower portions of the sides of the head is a pair of elastic bands 29, each band carrying at its center, a hair ornament 75 30 such as a rosette or bow of ribbon.

When one of the elastic bands is drawn upward, into position on top of the head, the other elastic band lies beneath the chin portion of the head having the face that is covered by the depending portion of the 80 hair.

The band that passes over the head holds the hair in proper position and thus the doll always has one face exposed and the other covered by the depending hair.

By lowering one elastic band and raising the other, and at the same time, properly manipulating the hair, either one of the two faces on the head may be exposed.

Obviously, the other covering or skin 10 90 of the doll may be made of any soft, readily workable fabric such as muslin, linen or silk, and in some instances, it may be found desirable to make the head covering of one kind of material and the body and limbs 95 from another material.

If desired, the doll's head or entire body may be dipped or coated with a waterproof material such as oil paint and which, when dry, renders the doll washable.

100 In some instances, it may be found desirable to use a section of wooly or fibrous material such as astrachan on the head to represent hair.

Doll heads, arms, and limbs constructed in 105 accordance with my invention may be used for replacing corresponding parts in other forms or makes of dolls.

Thus it will be seen that I have provided a relatively simple and practical fabric or 110 rag doll having a movable head, arm and limbs, said parts being very firmly secured to the body representing member and further, that I have provided simple and practical means whereby the doll's head is provided with two faces, either one of which may be readily exposed and the other covered by the hair that depends from the doll's head.

115 It will be readily understood that minor 120 changes in the size, form and construction of the various parts of my improved rag doll may be made and substituted for those herein shown and described, without departing from the spirit of the invention, the scope of 125 which is set forth in the appended claims.

I claim as my invention:

1. In a doll, a body having a fabric covering and a filling of fibrous material, there being an opening at the upper end of said 130

- body, a head member having a depending portion that projects through the opening at the upper end of said body and extends downwardly into the latter, a transversely disposed reinforcing wire arranged in the upper portion of said body beneath the shoulders thereof, a transversely disposed reinforcing tape arranged in the lower portion of said body, and a flexible member connecting the lower portion of said depending member with the central portion of said reinforcing tape in the lower end of said body member.
2. In a doll, a flexible body provided with sockets at the upper ends of its side portions, arms members having their rounded ends arranged in said sockets, discs located in the upper ends of said arm members a flexible member passing through the upper portion of said flexible body and the discs in said arm members and a reinforcing member of wire arranged in the upper portion of said flexible body, portions of which reinforcing wire are arranged in the shoulder portions of said body and the end portions of which reinforcing wire are formed into loops that are disposed adjacent to the sockets at the upper ends of the side portions of said body.
3. In a doll, a flexible body comprising an outer covering of fabric and a filling of fibrous material, there being an opening in the upper central portion of said body, a reinforcing member of wire arranged in the upper portion of said body and provided at its center with a loop that coincides with the opening in said body, portions of said reinforcing member to the sides of said central loop being arranged in the shoulder portions of the body, the ends of said reinforcing member being formed into loops that are positioned at the upper ends of the sides of said body, a flexible head representing member and a member depending therefrom, which last mentioned member passes through the loop at the center of said reinforcing member and occupies the opening in the upper portion of said body.
4. In a doll, a flexible body provided at its upper end with an opening, a reinforcing member arranged transversely within the upper portion of said body and provided with a centrally arranged loop that coincides with the opening in the body and a head member having a depending portion that extends through the opening in the upper portion of the body and through the loop in said reinforcing member, a flexible reinforcing member transversely arranged in the lower portion of said body, a flexible member connecting the lower end of the depending portion of the head member and the transversely arranged flexible member in the lower portion of said body, sockets formed in the upper side portions of the body, arms having rounded ends that are seated in said sockets, a transversely disposed flexible member passing through the upper portion of the body and into the upper ends of the arms and disks arranged within the upper ends of said arms, which disks are connected to said transversely disposed flexible member.
5. In a doll, a flexible body provided at its upper end with an opening, a reinforcing member arranged transversely within the upper portion of said body and provided with a centrally arranged loop that coincides with the opening in the body, a head member having a depending portion that extends through the opening in the upper portion of the body and through the loop in said reinforcing member, a flexible reinforcing member transversely arranged in the lower portion of said body, a flexible member connecting the lower end of the depending portion of the head member and the transversely arranged flexible member in the lower portion of said body, sockets formed in the upper side portions of the body, arms having rounded ends that are seated in said sockets, a transversely disposed flexible member passing through the upper portion of the body and into the upper ends of the arms, disks arranged within the upper ends of said arms, which disks are connected to said transversely disposed flexible member and leg-representing members flexibly connected to the lower corners of said flexible body.

In testimony whereof I affix my signature.
ELLEN M. MYTON,
